TRAFFIC CONTROL SYSTEM AND APPARATUS

Edward H. Eames, Old Greenwich, Conn., assignor to Automatic Signal Corporation, New York, N. Y., a corporation of Delaware

Application March 14, 1935, Serial No. 11,000

22 Claims. (CL 177—337)

This invention relates to traffic control systems and has for its general object to provide a new and improved traffic controlling system and apparatus therefor, capable of numerous different associations, but primarily designed for use at one or more of a plurality of intersections of a main traffic lane with several cross lanes. Briefly, the invention comprises apparatus for connecting and disconnecting controllers at individual intersections to or from a coordinated system, depending upon traffic conditions existing from time to time.

The term "coordinated system" or more generally the term "coordination" as used herein should be construed to mean any system of control of traffic signal timers or controllers at more than one intersection by which certain time relations are maintained between signal indications or signal changes at the several intersections.

Systems have heretofore been proposed for transferring right of way at the intersection of a main traffic lane with a cross traffic lane from the main to the cross lane at such times as traffic on the cross street may by appropriate means register its approach to the intersection. Other existing systems operate the control signals at a series of intersections, on a pre-arranged fixed time schedule regardless of immediate traffic densities or conditions, to accord right of way simultaneously to the main lane at all intersections for a predetermined period, and then to the side streets, or to transfer right of way to the side streets according to a pre-established progressive scheme.

Each of these systems above has certain disadvantages however. Individual traffic-actuated control systems, when installed at a series of closely spaced intersections without interconnections or other inter-co-ordination, frequently cause traffic on the main highway to stop at successive signalized intersections in periods of moderate or heavy traffic. In periods of light traffic, the fixed time co-ordinated systems impose unnecessary delay on traffic in the cross street during artery right of way periods if meanwhile there is no traffic proceeding along the thoroughfare, and in periods of heavy traffic vehicles on the artery awaiting right of way are needlessly delayed when there is no cross traffic, although the latter delay may be minimized with the progressive system. Another method of co-ordinating traffic actuated traffic control systems has also been proposed in which the response of local individual traffic-actuated signal controllers to traffic actuation is restricted to fixed periods

determined by a master control. This restriction is of benefit to main highway traffic and does not excessively restrict cross traffic in moderately heavy or heavy traffic, but it unduly penalizes cross traffic in light traffic conditions.

This invention provides means for bringing traffic signal controllers at individual intersections in a series under the control of a co-ordinated system when traffic conditions make this desirable, and releasing them when conditions make this desirable.

A primary object of this invention is to provide means for automatically releasing individual intersection controllers or groups of controllers from a master co-ordinating control when the main highway is infrequently interrupted, and for automatically reconnecting the individual control or controls when the main highway is frequently interrupted.

Another object is to provide means associated with an individual traffic controller to connect it to or disconnect it from a co-ordination system in accordance with the frequency of interruption of right of way on the main traffic lane in the co-ordinated system.

A further object is to provide means associated with an individual controller to maintain it under control of a co-ordinated system for a predetermined number of cycles of the co-ordinated system after each interruption of right of way on the main traffic lane at the individual controller.

An additional object is to provide a traffic control system in which there is a means associated with each individual controller for maintaining it under control of the co-ordination system for a predetermined length of time following each transfer of right of way from the main to the cross lane at the intersection where said controller is located.

Another object is to provide apparatus of this character which will co-ordinate a series of traffic actuated signal controllers along a highway without any interconnecting wires except the A. C. power supply, in which is provided means at an individual intersection controller to connect it to or release it from the co-ordination control in accordance with traffic actuation at the individual intersection.

Still another object is to provide apparatus employing a minimum of individually simple and well constructed parts such that the units upon assembling will comprise a system free from electrical and mechanical difficulties over long periods of time.

55

A still further object is to provide apparatus of this character which will be adaptable with a minimum of changes to be used with many different types of traffic-actuated traffic signal controllers.

5 Other objects will subsequently appear.

The invention will be described and its operation explained in detail in connection with the accompanying drawings, which illustrate practical embodiments of the invention and in which:

10 Figure 1 represents schematically a series of intersections and apparatus embodying the invention associated therewith to control movement of traffic through the intersections of the cross traffic lanes with the main traffic lane.

15 Figure 2 is a wiring diagram for a traffic signal controller and signals, and one type of co-ordinating unit including rotary controller, regulating switch and associated apparatus for setting and maintaining traffic signals at one of the intersections.

20 Figure 3 is a view of the lower bank of the regulating switch.

25 Figure 4 is a side view of the regulating switch.

25 Figure 5 is a view of the upper bank of the same switch.

30 Figure 6 represents a second type of co-ordinator, in which co-ordination is retained for a definite period of time, instead of for a certain number of cycles, following transfer of right of way from the artery.

35 Figure 7 illustrates a modification of the system in which the impulse generator for co-ordinating the individual controls is located at a central station.

Figures 8 and 9 are wiring diagrams for another form of simplified co-ordinating unit employing relays.

40 Figure 10 illustrates an alternative arrangement of the embodiment of the invention shown in Figure 2.

In Figure 1 of the drawings there is shown a complete, self-regulating system of traffic controllers installed at a series of intersections of a 45 highway or principal traffic lane A, with several cross vehicle lanes, B, C, Y, Z, which intersect or end at the highway.

50 A control system at street B, for example, may be comprised of three parts; a vehicle detecting or responsive device N, placed in or at the side of the cross street vehicle lanes, a control mechanism D, composed of electrical timing and switching means, and a signal indicating device S, for indicating to traffic when to go and when to stop. 55 Similar equipment may be located at each of the protected intersections of the group.

The signals utilized in the present system may consist of a housing in which colored lamps, lenses, and/or reflectors may be employed to display, for instance, green, red, and yellow, indicating respectively the right of way, interruption of right of way, and an impending change in right of way in the main and cross streets, in accordance with familiar practice. Any of a 65 number of well-known forms of signalling devices may be employed however in lieu of the type illustrated.

In the embodiments illustrated, pressure operated switches in the pavement units are operated 70 by the weight of vehicles traversing them, but any other form of device which will control an operating circuit upon the approach of a vehicle to the intersection may be employed. The pedestrian push buttons are erected where they will 75 be available for operation by persons desirous of

crossing the main traffic lane, and are connected in parallel with the vehicle detectors.

The control D may consist of two units; one, for timing the duration of the signal indications and effectuating change of these indications, may be any of several well-known types of traffic actuated controllers. Its operation may be governed by the vehicle and/or pedestrian responsive devices, so that control of right of way is 5 jointly regulated by the detecting means and the time control mechanism. The other unit forming a part of the control D is a coordination mechanism embodying the present invention and includes the apparatus for connecting and disconnecting the right of way signal controller above 10 to or from co-ordination control, depending upon traffic conditions existing at the particular intersection. 15

Some features of the system in controlling traffic are outlined as follows: first the operation 20 of a type of local signal controller independent of co-ordination at one intersection will be described, and then the operation of the co-ordinating mechanism.

When operating independently, in the absence 25 of traffic approaching the intersection on the side street, the local controller will indicate right of way to the highway A. A vehicle approaching on a side street, for instance street B, operates the actuating means N, and the controller, after causing a suitable warning to be displayed, transfers right of way from the highway to the cross street. Vehicles which operate the actuating means so 30 near the end of the side street right of way period that they have insufficient time to cross the intersection, affect the machine so that right of way 35 will eventually be returned to the side street without additional actuation of the side street detector. Whenever right of way is accorded to the highway, it cannot be retransferred to the 40 cross lane for at least a definite preestablished period, even if the side street detector should be actuated meanwhile.

Although operation of only one type of traffic-actuated signal controller has been described 45 here, co-ordinating mechanism embodying the present invention can be utilized in conjunction with many other forms of traffic actuated controllers including those provided with actuating means on the main highway, and those providing for variation of the side street right of way 50 period by actuation as well as others.

Two alternative systems for connecting to and disconnecting from co-ordination a traffic actuated traffic signal controller are disclosed herein. One type is shown diagrammatically in the lower portion of Figure 2. In this type, when, after a considerable period of absence of actuation, a vehicle actuates the detector in the associated side street and the right of way is transferred to the side street, there is brought into operation a means to prevent the right of way 6 transferring mechanism from again transferring right of way to the side street after its return to the highway, except at definite intervals in the cycle of a background co-ordinating controller, viz. the synchronous motor-driven cam-shaft R and its associated cams and contacts. This means is effective until a designated number of successive cycles of the background controller elapse following a transfer of right of way, in which cycles no traffic actuation is received. Controllers at the several intersections are similarly arranged, so that under conditions where more than one are operating in the co-

ordinated manner, right of way is transferred to all these side streets, either simultaneously or in accordance with some progressive scheme, for minimising multiple stopping on the main high-way.

The second type of system functions similarly to the one whose operation was just outlined, except that instead of maintaining the limiting influence of co-ordinated control for a certain number of cycles following transfer of right of way, co-ordination is retained for a definite length of time. A coordination mechanism embodying this principle is diagrammatically represented in Figure 6, and its operation will subsequently appear.

The details of construction of the coordination mechanism shown in the lower portion of Figure 2 will now be described and its use explained with the illustrative type of traffic actuated control mechanism shown in the upper portion of the same figure. Construction and operation of the latter will be described, but it will be appreciated that the present invention may readily be used, with or without certain changes in the wiring, with many other types of right of way transferring mechanism besides the one shown. The embodiments of the invention herein will therefore be construed as illustrative alone.

In Figure 2, 45 and 46 indicate power supply leads from any suitable source and to which, for example, the lamps 13-18 may be connected in a manner hereinafter described. These lamps are contained within the signal S, and similar sets are located within the similar signals at the other intersections controlled by the system.

A motor 19, which may be electrically driven, drives shaft 21, preferably through a reduction gear (not shown). A braking device, 20, which may be a magnetically operated friction brake, 40 may be employed to bring the motor quickly to a full stop and prevent revolution of the cam shaft 21 whenever the motor operating circuit is interrupted by relay F. On the shaft 21 are mounted a number of spaced, adjustable cams, 45 H, I, J, K, L, M each insulated from the cam-shaft. Each cam may consist of two discs, each having a hub on one side, mounted with their faces together and their hubs outside, so that the sector of the effective portion of cam having 50 major radius can be altered as desired by revolving one disc in respect to the other on the shaft. Each cam is held in its desired adjustment position and in its desired phase position on the shaft by set screws or other convenient 55 means. Operating in conjunction with each of the cams are one or more circuit-making and breaking members, so arranged that whenever the portion of the cam having the larger radius is rotated into conjunction with the circuit-making member, the latter is pressed into engagement with its mate, enabling the circuit to be closed. Contacts K1 and K2 which can thus be closed by cam K are disposed in series with artery green and side street red illuminating units 15 60 and 16, between leads 45 and 46. Likewise, units 13 and 18, artery red and side street green, are in series with contacts K3 and K4, and yellow units 14 and 17 are energized through contacts J1 and J2 and contacts I1 and I2 respectively.

70 The vehicle-actuated detector N and the pedestrian push button P in parallel with it are interposed between a relay E and ground. Also arranged between relay E and grounded lead 45, paralleling the detector circuit, is a lead 23 in 75 series with circuit breaker E3, E4, which is a

part of relay E, and circuit breaker L1, L2 operated by cam L. A relay F is connected directly to lead 46, and to lead 26 by two parallel circuits; one through lead 24, circuit breaker H2, H1 actuated by cam H, and lead 25; the other by lead 26, circuit breaker E1, E2, associated with relay E, lead 28 and circuit breaker G1, G2, which is a part of a third relay, relay G, whose function will be described hereinafter.

When relay F is energized, its armature F2, 10 engages with contact F1 and completes the circuit from leads 45, 26, to the motor 19, and when relay F is de-energized, the same armature F2 completes circuit through the braking mechanism 20 by engaging contact F3.

The position of the parts shown in Figure 2 is the normal resting position thereof in any one of the machines of the group. The operation of such a machine, if allowed to function independently, follows, starting in its resting position.

Signal units 15 and 16 will be energized by a current flowing through lead 25, contacts K1 and K2 and terminal 38 and accordingly right of way will exist on the artery. The camshaft will be in its rest position and stationary. If now a vehicle approaches along the side street at its intersection with the thoroughfare where the present controller is located, the vehicle will operate detector N, thereby momentarily energizing relay E. Relay E will continue to receive power, however, and remain "locked-in", by a circuit from lead 45, through lead 25, cam contacts L1, L2, lead 23, contact E4 and armature E3.

The relay E will also attract its armature E1, which, assuming for the present the energization of the co-ordinating relay G and closure of its contacts, will close a circuit from lead 45, through lead 28, contact E2, armature E1, lead 26 to motor-controlling relay F. This in turn pulls armature F2 away from contact F1, releases the brake mechanism 20, and by closing armature F2 against contact F1, energizes the motor 19 causing camshaft 21 to revolve slowly. As soon as camshaft 21 has rotated off the rest position, a circuit to relay F paralleling the one through circuit breaker E1, E2, lead 26, just described, supplies power for the remainder of the cycle to relay F through lead 24, contacts H1, H2, and lead 25, after relay E has become de-energized. Once the camshaft 21 has again reached the rest position, relay F must be energized through lead 26 for restarting, since contacts H1, H2, are open at this time.

Upon the starting of camshaft 21 from rest the movement of cams J and K will be such that by the closure of contacts J1, and J2, yellow will appear on the artery in addition to the green, and shortly thereafter these lights will be replaced by artery red 13 and side street green 18, 60 since contacts K3 and K4 will have come into engagement. Accordingly right of way will be transferred to the side street for a period of time determined by the shape and position of the cams and the speed of the camshaft.

At the termination of side street right of way interval, cam I causes yellow to appear on the side street by energizing unit 17 through contacts I1 and I2. Artery green, 15, and side street red, 16, are restored a few seconds thereafter 70 by cam K which closes contacts K1 and K2. This condition of the signal S will be maintained throughout the remainder of the revolution of the camshaft to resting position, and thenceforth until an actuation shall have been received either 75

by detector N or by push button P, whereupon the cycle already described is repeated.

Provision is made for "remembering" the approach along the side street of a vehicle which cannot immediately be granted right of way, by means of the lock-in circuit. Actuation of the detector N energizes relay E and causes armature E3 to close circuit with contact E4. Current then flows through leads 45, 25, circuit breaker 10 L1, L2, lead 23, contact E4, armature E3, relay E, to lead 29, and lead 46, and this continues to energize relay E until camshaft 21 has rotated to the side street green position. At this time cam L allows separation of contacts L1, L2, breaking 15 the circuit. Cam L may be adjusted to lock-in detector relay E during side street red and amber periods, and also during the last few seconds of side street green period so that a vehicle approaching the intersection and failing to cross 20 before right of way is shifted, insures that right of way will again be accorded to the side street at the earliest opportunity possible.

Before reviewing the operation of a co-ordinating unit embodying the invention, an element of one type of unit, the regulating switch, will be reviewed.

Referring to Figures 3, 4, and 5, two discs 79, 80, of insulating material are rigidly fixed together, and two annular parts 77 and 78, also of suitable insulating material, are supported coaxially by the discs 79 and 80. Within the parts 77 and 78 are mounted two disc-shaped members 81 and 82. The members 81 and 82 are firmly mounted on the shaft 83. Pressure in the spring 35 84 caused by the nut 85 keeps members 81 and 82 firmly pressed against the plates 79 and 80 respectively. For rotating the plates 81 and 82 with respect to the insulating discs there is a manually operated knob 86 and a pointer 87 to indicate 40 the amount of rotary displacement. A spring member 88 mounted on the underside of pointer 87 engages grooves 96 in the disc 87 for preventing the rotary portion of the switch from being set in a position where pointer 87 lies part way 45 between integers on the dial.

A number of spring contacts 88 are mounted on the insulating disc 77 so that the free ends of the contacts bear on the rotatable member 81. A corresponding number of contacts 89 are 50 mounted on disc 78 and their free ends bear on member 82. The fixed ends of all the contacts are adapted for connecting conductors thereto.

A commutator segment 90 of conducting material is securely mounted in the disc 81, in such a way that the upper surface of the segment is flush with the surface of the disc member. The arc of the periphery of commutating segment 90, engageable with the contacts of bank 88, extends over 180 degrees. Another commutating segment 92 is similarly embodied in disc member 82, its width, however, is equal to the span of one of the spring contacts, and is positioned to engage contact #2 on bank 88, when segment 90 is engaging contact #1 on bank 88; contact #3 65 when segment 90 is engaging contacts #1 and #2, and so on, depending upon the position of indicator 87.

Also forming a part of this embodiment is a rotary controller or line switch, which is of a type well known to those familiar with the art. It is 70 of the type frequently used in the dial switching systems of automatic telephony, and comprises a switch for selecting and connecting one circuit from a group of available circuits. It is operated by electrical impulsing. A switch of this char-

acter is diagrammatically shown in connection with Figure 2. Energization and de-energization of the line switch magnet T causes each of the three sets of wiper arms 72, 73, 74 to be stepped ahead one contact on each of their respective 5 contact banks.

Referring now to the lower part of Figure 2, one complete control mechanism for automatically placing the individual traffic actuated controller under co-ordinated control or releasing it 10 from co-ordinated control in accordance with the invention will be described.

Wires 45 and 46 indicate power supply leads from an alternating current source, and from which by leads 47 and 48 a synchronous motor 49 15 receives power. The motor 49 operates continuously, and drives shaft 50, on which is mounted an adjustable cam R, insulated from the cam-shaft. This cam is similar in construction and in its mounting on the shaft 50 to the cams on 20 shaft 21 described above. Likewise the circuit breaker R1, R2, can be of type similar to those disclosed above.

A circuit from lead 45 through lead 47, lead 69, cam-operated circuit breaker R1, R2, lead 99 25 to terminal 61, and in turn by wire 1, terminal 32 of the right of way controlling mechanism and co-ordinating relay G, which by leads 29, 46, is joined to power, energizes relay G when R1 and R2 are periodically closed.

Each of the banks of contacts 83, 84, 85 of the rotary controller contains eleven contacts, and each contact of bank 83 is connected to a corresponding contact in the upper bank of contacts 89 of the regulating switch. Connection is 35 also made between each contact of bank 84 (except contact #11) and the corresponding contacts 1-10 on the lower bank of the regulating switch. Wiper 72 on the top bank of the line switch is connected directly to the grounded power lead 45, and the wiper or commutating arm bearing on the upper banks of contacts 89 of the regulating switch is connected to lead 99 thus providing a second circuit to energize the relay G. In order for camshaft 21 of the right of way 45 controller to leave its rest position, the relay G must be energized through either one of these circuits and relay E must be locked-in, by detector actuation. The employment at other intersections of cams similar to cam R and driven by 50 similar synchronous motors connected to the same power supply maintains a constant phase relation of the cyclic closure of cam contacts R1, R2 at the several intersections, and provides the basic means for co-ordinating the individual intersection right-of-way controllers.

Direct current for operating the magnet T of the line switch is supplied through leads 62, 63 from a rectifier 64 or other suitable controlled direct current source. A filter condenser 65 is 60 interposed between leads 62 and 63 for maintaining a near-constant voltage value.

The rectifier 64 operates from alternating current in leads 45, 46. Lead 66 electrically connects one input terminal of the rectifier 64 to lead 46. The other terminal is joined to lead 45, by lead 67, through wiper arm 74 of the stepping switch, contact bank 85, and lead 70 which is in series with contact U2, armature U1 of a relay U, and in series with contact T2, armature T1 70 which latter are operated by line switch magnet T.

In all contact positions of the wiper 74 except position #1, the circuit through wiper 74 is completed on bank 85 to contact U2, so that when 75

relay U is energized, this circuit in lead 70 supplies power to the rectifier 64, which in turn energizes line switch magnet T. Magnet T breaks the circuit to the rectifier between armature T1 and contact T2, and magnet T is again de-energized. Each time the magnet T is energized and de-energized, the stepping mechanism of the line switch advances the wipers over their respective banks one contact. Hence when relay U is energized (with the side street green signal as will be explained subsequently), wipers will automatically be advanced by the rapid stepping circuit of lead 70 from the position in which they were resting to the position where each wiper engages contact #1 on its associated bank.

A circuit through wiper 73 also may energize the line switch magnet T. When wiper 73 engages a contact on bank 84 which by the regulating switch is connected to commutating segment 90, the circuit from lead 61 to ground is completed over segment 90, lead 68, circuit breaker R1, R2, leads 69, 41, 45 to ground. Thus under this condition once during each cycle of camshaft 50 when contacts R1, R2, are made and broken, magnet T is energized and de-energized, advancing the wipers one contact. The effect of this is to count revolutions of the cam shaft 50 which corresponds to counting cycles of the background coordinating controller.

One terminal of the relay U is connected to power lead 46 by lead 100, but the relay is energized only when the traffic signal at the intersection is indicating green to the side street, since the other terminal of relay U is connected to ground by lead 71, wire 2, lead 34, circuit breaker K4, K3, lead 25 and grounded lead 45. Contacts K3, K4 are closed only during the side street right of way period. The effect of this is to reset the counting of cycles of the background coordinating controller each time the right of way is transferred to the side street.

The regulating switch provides a ready means to alter the number of cycles of camshaft 50 to be counted following last prior transfer of right of way from the highway and thus adjusts the number of such cycles during which co-ordinated operation of the signal is assured, after each transfer of right of way to the side street, and after which the right of way transferring mechanism is released from control by contacts R1—R2 of the coordinating controller. Assuming that it is desired to release the signal from co-ordination during the third successive cycle of the coordinating controller after the last preceding transfer of right of way from the highway, (which it will be noted is the third successive actuation-less cycle or cycle without traffic actuation), the indicator #1 of the regulating switch, which may be set at any number between one and ten inclusive, is accordingly placed on 3, so that commutating member 92 on the upper bank of the regulating switch will engage contact #3 of bank of contacts 89. In this position, commutating segment 90 will simultaneously engage contacts 1 and 2 of lower bank of contacts 88, and the other contacts on these banks of the regulating switch will remain disconnected.

Operation of this mechanism, in regulating the traffic-actuated right of way transferring controller, at any particular intersection assuming for example the setting of the regulating switch indicator #1 to be set at three cycles, follows.

Assume, for example, for a starting position, that wiper arms 72, 73, 74 of the rotary line switch are each engaging contact #3 on their

respective banks, and that camshaft 21 of the controller is in its resting position. Camshaft 50 will be revolving continuously at constant speed, the length of time required for each revolution is somewhat greater than that required by one revolution of camshaft 21.

Current will flow from grounded lead 45, wiper 72, contact #3 on bank 83 of the line switch, and contact #3 on upper bank 89 of the regulating switch, commutating arm 92, lead 89, wire 1, through relay G, lead 29 to power lead 46. Consequently relay G will be energized, and will close armature G1 against contact G2. Whenever these contacts are closed, the right of way transferring mechanism is in condition to start immediately from its rest position for transferring right of way in response to actuation of detector N which energizes relay E.

Therefore, if a vehicle now approaches along the side street B, for example, detector N will be operated whereupon relay E will be locked-in in exactly the same manner described in connection with the operation of the right of way transferring mechanism independently. A circuit from lead 46, through relay F, lead 28, armature E1, contact E2, lead 28, armature G1, contact G2, to ground is thereby completed, energizing relay F and starting the motor.

When camshaft 21 revolves to the side street green position where cam contacts K3, K4 are closed, relay U is energized by a circuit from power lead 46, through lead 100, relay U, lead 11, wire 2, lead 34, circuit breaker K4, K3, lead 25, lead 45 to ground. During periods when relay U is energized, circuit is completed to operate rectifier 64 through lead 67, wiper, 74, contact #3 on bank 95 of the line switch, lead 70, circuit breakers U1, U2, and T1, T2, and grounded lead 45. Direct current thus is applied to leads 62, 63 energizing the line switch motor magnet T which breaks the circuit to the rectifier between armature T1, contact T2, and immediately de-energizes the magnet T again. Energizing and de-energizing the magnet T causes the wipers 72, 73, 74 to advance one contact on their respective banks. The relay U remains energized until the end of the side street green interval. Hence the circuit in lead 70 to the rectifier is again completed, through armature T1, contact T2, and now through contact #4 instead of #3, on the bank 95, and the stepping operation of the line switch is repeated until the wiper arms of the switch engage contact #1 where there is no further connection on bank 88, nor on any other bank, to again energize rectifier 64 under this condition.

Permissive co-ordinating relay G becomes disconnected from power when wiper 72 leaves contact #3. For this reason when camshaft 21 has revolved through the side street green position and returned to its rest position where right of way is accorded to the artery it cannot again be revolved in response to detector actuation until relay G is energized.

During that part of each cycle of the constantly revolving cam shaft 50 when cam contact R1, R2 are closed, a circuit through contacts R1 and R2, lead 99, contacts R1 and R2, wire 1 energizes relay G. Therefore, at this time, once during each cycle of cam shaft 50, motor 19 will be started for transfer of right of way in response to any detector actuation which has occurred and which will have locked-in relay E after the last transfer of right of way. Regardless of the position of the line switch wiper, whenever right

of way is so transferred to the said street, relay U is energized by the circuit from leads 45, 25, through circuit breakers K3, K4 (which are closed during the artery red-side street green interval), 5 wire 2, leads 71, 100, 46, thus completing the line switch self-stepping circuit between contact U2 and armature U1, and the wipers are automatically stepped around to contact #1, in the manner described above, thus resetting the coordination release mechanism in preparation for recommencing the cyclic stepping of the wipers by contacts R1, R2 and resultant counting of actuation-less cycles of shaft 50, i. e., the counting of cycles of the coordinating controller during which 10 the artery green signal is displayed continuously by the right of way controller in the absence of traffic actuation.

Thus if no traffic actuation occurs the successive making and breaking of contacts R1—R2 in 20 successive cycles steps the line switch ahead successively one step per cycle until it reaches the point where it energizes relay G independently of contacts R1—R2, which in the illustration described occurs in the third cycle. If for instance, 25 no traffic actuation occurs in the first cycle but does occur in the second cycle, the right of way controller will transfer right of way to the cross street as soon as the contacts R1—R2 are closed in the second cycle and when the right of way is 30 given to the cross street the stepping switch will very rapidly be self stepped back to position 1. If traffic actuation is received only at the end of the third cycle or thereafter the right of way controller does not have to wait for the next closing of contacts R1—R2 but can transfer right of 35 way immediately, and as before when right of way is given to the cross street the stepping switch is stepped rapidly back to its initial position.

While the co-ordinator regulating switch is set 40 for release from co-ordination in the third actuation-less cycle following right of way transfer, and when the line switch wipers are engaging either contacts #1 or #2, the cyclic closure of contacts R1, R2 also completes the line switch 45 notching circuit from leads 45, 47, 69, contacts R1, R2, lead 68, segment 90, contacts on banks 88 and 84, wiper 73, lead 67 to energize the rectifier 64. The energizing of the line switch magnet 50 T and the consequent deenergizing thereof, when cam contacts R1, R2 separate, advances the wipers one contact each time, in the aforescribed manner.

When cam shaft 50 has completed two successive revolutions in which no detector actuations 55 are received, the next closure of contacts R1, R2 completes the line switch magnet energizing circuit, and the wiper arms 72, 73, 74 are thereupon advanced to contact #3 on their respective banks.

When wiper 72 again engages contact #3 on bank 93, the circuit from power lead 46, lead 29, relay G, wire 1, lead 99, contacting arm 92 of the regulating switch, contacts #3 on banks 89 and 93, wiper arm 72 to grounded lead 45, for energizing 60 relay G is once more completed. In this position therefore, with relay G energized, the right of way transferring mechanism is released from the limiting of the coordinating unit and upon actuation of detector N will forthwith accord right of 65 way to the cross lane.

It is apparent that in lieu of setting the regulating switch indicator at 3, it may be set at any integer between 1 and 10, whereupon in the cycle indicated following last previous transfer of right 70 way, the relay G will be energized, permit-

ting independent response of the controller to actuation.

It will thus be observed that the release mechanism including the stepping switch in effect counts successive cycles of cam shaft 50 of the 5 coordinating controller during which there is no traffic actuation, the mechanism being reset each time right of way is transferred to the cross street in response to actuation to count again when right of way returns to the highway. While the 10 right of way is on the highway the counting continues only until a predetermined number of such successive actuation-less cycles—which may be preset on the regulating switch—have been counted whereupon the right of way controller 15 is released from the restriction of the coordinating controller and the next transfer of right of way may be made immediately in response to actuation and independent of the coordinating controller. 20

If desired, an alternative circuit may readily be substituted for the arrangement involving the relay G and the cam R described, in which case a second cam, Q, is added to shaft 50, as shown in Figure 10. In this event relay G and its contacts may be eliminated from the right of way controller. Terminal 32 is connected directly to lead 28, and that portion of lead 99 connecting with contact R2 is removed. Cam Q makes and breaks its contacts simultaneously with cam R. 30

Relay G and the alternative above described provide ways of eliminating possible feedbacks between the right of way controller and the stepping switch counting mechanism while right of way is being accorded to the side street and contacts R1, R2 are open. 35

In order that repeated transferring of right of way at a series of intersections will necessitate only a minimum of stopping of traffic proceeding along the artery, the cam shaft 50 in every 40 machine is revolved at the same speed in a cycle of the same length. Thus each pair of contacts R1, R2, operated by cam R and mounted on each shaft 50, may be arranged to close in a definite phase relationship with the others. Either all 45 pairs may be operated to close simultaneously or according to a predetermined scheme. Therefore, when the right of way controllers are operating under the control of the co-ordinating units, right of way is transferred to all cross lanes having 50 actuation in accordance with the pre-established scheme. After the required number of revolutions of camshaft 50 following last prior transfer of right of way, during periods when transfer of right of way to the cross lanes is 55 infrequent, right of way transfer to a cross lane may be made independently of the co-ordination restriction immediately upon actuation.

As an alternative arrangement for the control mechanism shown in the lower part of Figure 2, 60 a time relay may be substituted for the line switch and regulating switch in the co-ordinating unit disclosed. An embodiment utilizing this arrangement is diagrammatically shown in Figure 6. The relay O, conveniently of the retarded drop-out type, is connected to be energized through wire 2, leads 131, 132, upon transfer of right of way from the artery. At the end of a predetermined period after the last prior transfer of right of way to the side street preferably a period 65 equivalent to one or more cycles of the coordinating unit, the length of said period being determined by the setting of the time-delay relay O, circuit is again completed by armature O1, and contact O2 to energize the local co-ordination 70 circuit. 75

relay G at terminal 32 which then permits the controller to respond promptly to further actuation. It will be obvious to those skilled in the art that in lieu of the exact arrangement shown in Figure 6, a retarded pickup time relay could be employed, to be energized during the highway right of way period, and close its contacts to energize local relay G after a predetermined time.

The invention does not necessarily embody a synchronous motor driven camshaft with cams mounted thereon. The impulses from grounded side of power supply for stepping ahead the line switch wipers and cyclically energizing co-ordination relay G, furnished in embodiment of Figure 2 from leads 45, 47 by cam R when its contacts R1, R2 are made to engage, may be supplied from any convenient type of impulse generator which may be located, for example as in Figure 7, at a central station and transmitted to each individual co-ordinating mechanism.

In Figures 8 and 9 are shown further alternative, simplified forms of the co-ordinating unit, which may be substituted for the unit comprising the lower part of Figure 2. The types shown in Figures 8 and 9 will respectively retain the right of way controllers with which they operate under co-ordination for one and two revolutions of the camshaft 50 following the last prior transfer of right of way to the cross lane. This arrangement utilizes cams and relays, and the line switch and regulating switch are eliminated.

Referring again to the upper unit of Figure 2, there is mounted on camshaft 21 a cam M, arranged to close the pair of contacts M1, M2 when camshaft 21 is in the rest position. Contact M1 is connected to leads 29, 46; contact M2 to terminal 31. Now referring to Figure 8, relay V is connected between terminal 31 and contact R2 by wire 3, leads 125, 126. A circuit from lead 47 passes through contacts V1, V2, then through lead 128, wire 1 to contact 32 and co-ordinating relay G of the right of way controller; a second circuit from lead 47 is a lock-in circuit for relay V, and includes contacts V3, V4, and lead 127 to lead 126.

Assume that the camshaft 21 is in its rest position, during which right of way is displayed to the highway. Synchronous motor 49 constantly rotates shaft 50 and periodically contacts R1, R2 make contact with each other, thus energizing relay V through leads 126, 125, wire 3, contacts M2, M1, leads 29, 46. Relay V remains energized by the lock-in circuit from lead 47 across armature V3, contact V4. Another armature of relay V, V1, energizes contact V2 and completes circuit to the co-ordination relay G, whereupon camshaft 21 may be revolved in response to detector actuation. By leaving the rest position, camshaft 21 interrupts the energizing circuit to relay V between contacts M1, M2, and thus further response to actuation by the controller is not possible until shaft 21 has again reached its rest position and co-ordinating contacts R1 and R2 engage.

Similar arrangements in which the line and regulating switches are dispensed with may be set up for retaining coordination for any desired number of cycles of the camshaft 50 following last previous right of way transfer to the side street. Figure 9 shows such a system whereby coordination is retained over two cycles. When the apparatus of Figure 9 is used in conjunction with the traffic actuated signal controller forming the upper part of Figure 2, contact M1 of the con-

troller is connected to leads 25 and 45 to minus, instead of to leads 29 and 46 to plus as shown.

Cam Q makes and breaks its contacts Q1, Q2, and Q3, Q4 just before the cam R closes contacts R1, R2. During the first cycle of shaft 50 after shaft 21 has returned to rest position the contacts R1, R2 close, energizing and locking-in relay X, and in the next cycle circuit to energize relay W is completed through contacts Q1, Q2 and armature X1, contact X2. The function of relay 10 W, similar to that of relay V in Figure 8, is to energize permissive co-ordinating relay G. The closing of contacts Q3, Q4 during each cycle periodically energizes the relay G through lead 130, to permit response of the controller to actuation 15 once per revolution of shaft 50. It is desirable that the time cycle of shaft 21 be somewhat less than the time cycle of shaft 50.

Summarizing, it will be seen from the foregoing that the structures illustrated in the lower 20 part of Fig. 2, and in Figs. 6, 7, 8 and 9 are alternative coordination and coordinating release arrangements for use with a right of way transferring mechanism of the type shown in the upper portion of Fig. 2 or with other well-known 25 corresponding types of such mechanism, and that all of these alternative coordination mechanisms have a common purpose. Thus, in periods when transfer of right of way from the main highway at an intersection is made frequently, the right 30 of way transferring mechanism thereat is connected to and retained under the control of the coordinating controller unit in order that such transfers will be made in predetermined relation with the coordinated system at times determined 35 by the coordinating controller. When the time frequency of interruptions to the main highway traffic decreases sufficiently the local right of way transferring mechanism is released from the co-ordinating controller so that right of way can be 40 transferred to the side street immediately in response to traffic actuation and consequently delays to cross street traffic will be minimized. As pointed out above the frequency of interruption is measured under certain alternative arrangements by counting up to a certain point the number of cycles of the coordinating controller during which no transfer of right of way from the highway has occurred by the right of way controller and under other alternative arrangements 50 this frequency is determined by measuring up to a certain point the time after any transfer of right of way from the highway and during which no transfer of right of way occurs. In either case when the certain point is reached the right 55 of way controller is automatically released from the coordinating controller until the next transfer of right of way from the highway when the right of way controller is again placed under the control of the coordinating controller. 60

From the foregoing it will be appreciated that embodiments of the present invention obtain the advantages of coordinated traffic control for a series of intersections in heavy traffic conditions, without imposing unnecessary delay to cross lane 65 traffic in light traffic periods, since in the latter periods for a large part of the time right of way can be allowed them promptly upon actuation of the detectors, independent of any co-ordination control if the main highway has had a considerable period of right of way free from interruption. Thus the specific objects enumerated and others are achieved. It is understood that various modifications may be made in the design and structural details herein exemplified, without de- 70 75

parting from the spirit of the invention as defined by the claims.

Having described my invention what I claim as new and desire to secure by Letters Patent of the United States is as follows:

- 5 1. In a traffic signal control apparatus for the intersection of a cross lane with a main traffic lane having a traffic actuatable means in the cross lane and a right of way transferring controller connected to said traffic actuatable means for normally according right of way to the main traffic lane and operable thru a cycle to transfer right of way to the cross lane and retransfer right of way to the main lane, means forming a 10 part of the controller for initiating cyclic operation of the controller in response to actuation of said actuatable means, a master control means for periodically determining when cyclic operation of the controller may be initiated in response to actuation, and a means for releasing the cyclic operation initiating means from such determining effect by the master control means a predetermined period after the last transfer of right of way from the main lane.
- 15 2. In a traffic signal control apparatus for the intersection of a cross lane with a main traffic lane having a traffic actuatable means in the cross lane and a right of way transferring controller connected to said traffic actuatable means for normally according right of way to the main traffic lane and operable thru a cycle to transfer right of way to the cross lane and retransfer right of way to the main lane, means forming a 20 part of the controller for initiating cyclic operation of the controller in response to actuation of said actuatable means, a master control means for periodically determining when cyclic operation of the controller may be initiated in response to actuation, and a time controlled switch means operating at the end of a predetermined time period of continuous right of way on the main lane longer than the period of such periodic operation of the master control to release the cyclic 25 operation initiating means from such determining effect by the master control means to permit the initiating means to function immediately upon actuation independently of such determining effect until the next transfer of right of way to the main lane.
- 30 3. In a traffic signal control system for an intersection of a cross road with a main highway having a right of way according and transferring mechanism and a master control connected to the right of way controlling mechanism and cyclically operable to determine the time when transfer of right of way by said mechanism to the cross road may occur, traffic actuated means associated with said cross road, means associated with the right of way transferring mechanism to cause right of way to be accorded normally to the main highway and solely upon actuation of said traffic actuated means to cause transfer of right of way to its cross road at the time determined by said master control and thereafter retransfer right of way to the main highway, and means operable a predetermined time after said retransfer to release said mechanism from such determining effect by said control and so affect said mechanism that it will transfer right of way immediately upon actuation at any time independently of such determining effect of said master control.
- 35 4. In a traffic control system for the intersection of a cross road with a main highway having a traffic actuatable means in the cross lane and a right of way transferring mechanism, said mechanism normally according right of way to the main highway and adapted upon actuation of said traffic actuatable means to transfer right of way to the cross road and then retransfer it to the highway, a master control timer connected to said right of way transferring mechanism and operable cyclically to control said mechanism in a part of its cycle preventing said mechanism from operating in response to actuation of said traffic actuatable means and in a second part of its cycle causing response to actuation occurring in either part of such cycle, means connected to said master timer and said mechanism and operable after a predetermined interval of time longer than the timer cycle and in which right of way remains continuously on the highway to render said mechanism immediately responsive to the first actuation occurring thereafter in any part of the timer cycle.
- 40 5. In a traffic signal control apparatus for the intersection of a cross lane with a main traffic lane having a traffic actuatable means in the cross lane and a right of way transferring controller connected to said traffic actuatable means for normally according right of way to the main traffic lane and operable thru a cycle to transfer right of way to the cross lane and retransfer right of way to the main lane, means forming a part of the controller for initiating cyclic operation of the controller in response to actuation of said actuatable means, a master control means for periodically determining when cyclic operation of the controller may be initiated in response to actuation, and a time controlled switch means operating at the end of a predetermined time period of continuous right of way on the main lane longer than the period of such periodic operation of the master control to release the cyclic operation initiating means from such determining effect by the master control means to permit the initiating means to function immediately upon actuation independently of such determining effect until the next transfer of right of way to the main lane.
- 45 6. In a traffic signal control system for the intersection of a cross road with a main highway having a right of way transferring mechanism at the intersection and traffic actuatable means in the cross road, said mechanism normally according right of way to the main highway and adapted upon actuation of said traffic actuatable means to transfer right of way to the cross road and then retransfer it to the highway, a master control connected to said right of way transferring mechanism and effective immediately after any such retransfer to the highway to provide a cyclically repeated time cycle of control therefor in a part of which cycle said mechanism is prevented from so transferring right of way from the main highway upon actuation and in the other part of which cycle said mechanism is permitted to so transfer right of way immediately upon actuation, and means associated with said mechanism and operable after a predetermined interval of right of way on the highway longer than one such time cycle to render said master control ineffective over said mechanism and to permit said mechanism to so transfer right of way immediately in response to actuation occurring in any part of the master time cycle independent of said master control.
- 50 7. In a traffic signal control system for the intersection of a cross road with a main highway having a right of way transferring mechanism at the intersection and traffic actuatable means in the cross road, said mechanism normally according right of way to the main highway and adapted upon actuation of said traffic actuatable means

to transfer right of way to the cross road and then retransfer it to the highway, a master control connected to said right of way transferring mechanism and to provide when effective a 5 cyclically repeated time cycle of control therefor in a part of which cycle said mechanism is prevented from so transferring right of way from the main highway upon actuation and in the other part of which cycle said mechanism is 10 permitted to so transfer right of way immediately upon actuation, and means associated with said mechanism and operable after a predetermined interval of right of way on the highway longer than one such time cycle after transfer 15 of right of way to the cross road to render said master control ineffective over said mechanism and to permit said mechanism to so transfer right of way immediately in response to actuation occurring in any part of the master time cycle in 20 dependent of said master control, means operated by said mechanism upon any such transfer and retransfer of right of way to render said master control so effective immediately after such retransfer to the highway.

25 8. A traffic signal control apparatus for the intersection of a main traffic lane with a cross lane having traffic actuatable means in the cross lane, a right of way transferring controller for according right of way normally to the main lane 30 and upon actuation of said traffic actuatable means transferring right of way to the cross lane and retransferring it to the main lane again, master control means connected to said controller to provide a cyclically repeated time cycle 35 in a part of which cycle transfer of right of way is permitted immediately in response to actuation, and in the remaining part of the cycle transfer of right of way is postponed until the end of such remaining part of the cycle, and 40 means operable after a predetermined period longer than one such time cycle has elapsed during which right of way has remained continuously on the main lane to render said master control means ineffective until after the next actuation occurring at any time thereafter as long as right of way remains on said main lane, whereby right of way is transferred immediately in response to such actuation.

9. A traffic signal control system for the intersection of a cross traffic lane with a main lane having, in combination, a traffic actuatable device in the cross lane, a traffic signal controller connected to the traffic actuatable device for controlling a traffic signal to accord right of way 55 normally to the main lane and upon actuation of the said actuatable device to transfer right of way to the cross lane, a master control unit connected to said controller and including a cyclic mechanism operable through a cycle and 60 having means effective upon transfer of right of way from the main lane by said controller for restricting said controller from again transferring right of way from the main lane except at a predetermined point in the cycle of said cyclic 65 mechanism in response to actuation occurring at or prior to said point, and further means operable after a predetermined number of cycles when and during which there has been no transfer of right of way from the main lane to release said 70 controller from the restricting effect of said restricting means and to permit immediate transfer in response to the next actuation at any time.

10. In a traffic signal control system for the 75 intersection of a cross road with a main high-

way having a right of way transferring mechanism at the intersection and traffic actuatable means in the cross road, said mechanism normally according right of way to the main highway and adapted upon actuation of said traffic actuatable means to transfer right of way to the cross road and then retransfer it to the highway, a master control connected to said right of way transferring mechanism and effective immediately after any such retransfer to the highway to 10 provide a cyclically repeated time cycle of control therefor in a part of which cycle said mechanism is prevented from so transferring right of way from the main highway upon actuation and in the other part of which cycle said mechanism is 15 permitted to so transfer right of way immediately upon actuation, and means associated with said mechanism and operable after a predetermined number of such cycles of the master control occurring while right of way is continuously 20 accorded to the main highway to render said master control ineffective over said mechanism and to permit said mechanism to so transfer right of way immediately in response to actuation occurring in any part of the master time 25 cycle independent of said master control.

11. In a traffic signal control system for the intersection of a main lane with a cross traffic lane, the combination of a traffic actuated device in the cross lane, a traffic signal controller connected to said actuatable device for according right of way normally to the main lane and in response to actuation of the actuatable device transferring it to the cross lane and after a predetermined period retransferring right of way to 30 the main lane, and a master control unit associated with the right of way controller operable through a cyclically repeated cycle to govern operation of said controller, each such cycle of said master control unit having a first and second 35 part, means including a circuit closed only in the second part of such cycle for permitting said controller to transfer right of way to the cross lane in response to actuation of said traffic actuatable means occurring in the first or second part of the 40 control unit cycle and means for opening said circuit in the first part of the cycle for preventing said controller from transferring right of way during said first part of the cycle, and further 45 means operable after a predetermined number 50 of cycles of the master control unit have elapsed during which there has been no transfer of right of way from the main lane to render said right of way controller immediately responsive to the first actuation occurring thereafter in any part 55 of the time cycle.

12. A traffic signal control apparatus for the intersection of a cross traffic lane with a main lane having a traffic actuatable device in the cross lane and a right of way transferring controller connected to said traffic actuatable device, and normally resting to accord right of way to the main lane and operable when started to transfer right of way to the cross lane for a predetermined period and then to retransfer right of way to the 60 main lane and return to rest, a master timer connected to said controller and comprising a circuit when closed for starting said controller, a cam operated circuit closer closed periodically for predetermined intervals alternated with opening 65 thereof for predetermined intervals for preparing said circuit only during intervals of closure, means operable upon actuation of the traffic actuatable device in the cross lane to complete said circuit when prepared for starting said controller, 70 75

means for counting successive periodic closings of said circuit closer in preparing said starting circuit when and during which there is no right of way transfer from the main lane, means operable after a predetermined number of said closings to continuously prepare said starting circuit for immediate completion thereof by said circuit completing means operable upon actuation of said actuatable device, and means operable upon the next transfer of right of way from the main lane to render said last named means inoperative again until a further predetermined number of said closings has again been counted.

13. A traffic signal control system for the intersection of a cross lane with a main traffic lane having, in combination, a traffic actuatable device in the cross lane, a traffic signal controller connected to said actuatable device for according right of way normally to the main lane and when permitted, transferring right of way to the cross lane for a predetermined period in response to actuation of said cross lane actuatable device, and, connected to the controller, means including a circuit and operable only when the circuit is closed for permitting the controller to transfer right of way to the cross lane in response to actuation of said actuatable device, means for closing and reopening said circuit periodically to restrict the time of transfer of right of way from the main lane to such periodic closings of said circuit, a rotary step-by-step switching mechanism having a starting position and a series of other positions through which it is stepped periodically by such periodic closings of said circuit, means operated by the step-by-step switching mechanism after a predetermined number of successive closures of said circuit for permitting the controller to transfer right of way to the cross lane at any time in response to actuation of the actuatable device, and means operable upon the next transfer of right of way from the main lane to reset said step-by-step switching mechanism to its starting position to render said last means ineffective so as to again restrict transfer by the controller in response to actuation of said actuatable device to such periodic closings of said circuit.

14. A traffic signal control apparatus for the intersection of a cross lane with a main traffic lane including a traffic actuatable device in the cross lane, a right of way transferring control connected to said traffic actuatable device and normally according right of way to the main lane and in response to actuation of the said actuatable device operable through a cycle in which right of way is accorded to the cross lane and then retransferred to the main lane, means for storing the effect of actuation while right of way is on the main lane until right of way is transferred to the cross lane in response thereto, a periodic timer associated with the controller and operable upon transfer of right of way to the cross lane to time a time period longer than the right of way cycle of said controller, means operable upon transfer of right of way from the main lane to prevent further transfer of right of way from the main lane except at the completion of the time period by the associated timer whereupon such transfer is permitted in response to actuation occurring in the time period, and further means operable upon completion of a predetermined number of timing periods when and during which there has been no transfer of right of way to release the right of way transferring controller from the restricting effect of

the preventing means and to permit immediate transfer of right of way in response to the next actuation.

15. In a traffic signal control system for the intersection of a cross traffic lane with a main lane having a traffic actuatable means in the cross lane, right of way transferring mechanism connected to said traffic actuatable means normally according right of way to the main lane and upon actuation of said traffic actuatable means transferring right of way to the cross lane and after a predetermined period retransferring right of way to the main lane, means for storing the effect of actuation of said actuatable means when right of way is on the main lane until right of way is transferred in response to such actuation, and a cyclic master timer operating in cycles for determining fixed periods in such cycles only during which periods can the right of way transferring mechanism respond to actuation of the actuatable device during such cycle, an apparatus comprising means operable upon transfer of right of way from the main lane for automatically connecting said right of way transferring mechanism to said cyclic master timer, means for counting successive cycles of said timer when and in which there is no transfer of right of way from the main lane and operable upon completion of a predetermined number of cycles automatically to release said right of way transferring mechanism from such determining effect by such master control timer.

16. In a traffic signal control system for the intersection of a cross traffic lane with a main lane having a traffic actuatable means in the cross lane, a right of way transferring mechanism connected to said traffic actuatable means normally according right of way to the main lane and upon actuation of said traffic actuatable means transferring right of way to the cross lane and after a predetermined period retransferring right of way to the main lane, means for storing the effect of actuation of said actuatable means when right of way is on the main lane until right of way is transferred in response thereto, and a cyclic master control timer operating in cycles for determining fixed periods in such cycles only during which periods can the right of way transferring mechanism respond to actuation of its traffic actuatable device, an apparatus comprising means operable upon transfer of right of way from the main lane for automatically connecting said right of way transferring mechanism to said cyclic master control timer, means operable after a predetermined number of cycles of the said cyclic timer in which there has been no transfer of right of way from the main lane automatically to release said right of way transferring mechanism from such determining effect by said master control timer, and adjusting means including a manually operated switch for altering said predetermined number of cycles of the cyclic master control timer before the right of way transferring mechanism is automatically released.

17. A traffic signal control system for the intersection of a cross traffic lane with a main lane and having traffic actuatable means in the cross lane, a right of way transferring mechanism normally resting to accord right of way to the main lane and upon actuation of the actuatable means operable through a cycle in which right of way is transferred to the cross lane and thereafter retransferred to the main lane, means for storing the effect of actuation of said actuatable

- means when right of way is on the main lane until right of way is transferred in response thereto; cyclic master control means operating in cycles and associated with the right of way transferring mechanism for limiting transferring of right of way from the main lane to once per cycle of said master control means, means including a rotary stepping switch for counting successive cycles of said master control means 5
- 10 when and during which there is no transfer of right of way from the main lane, means operable after a predetermined number of said successive cycles for releasing said right of way transferring mechanism from such limiting effect of the master control means for allowing immediate transfer of right of way in response to actuation, means operable upon the next transfer of right of way from the main lane to reconnect the master control means to said transferring mechanism to reestablish such limiting effect, and 15 adjusting means comprising a manually operated switch for altering said predetermined number of cycles of said master control means.
18. A traffic signal control system for a series of intersections of cross lanes with a common main traffic lane having at each intersection, in combination, a traffic actuatable device in the cross lane, a traffic signal controller connected to the actuatable device in the cross lane 20 thereat for according right of way normally to the main lane and when permitted, transferring right of way to the cross lane for a predetermined period in response to actuation of said cross lane actuatable device, and, connected to the controller, means including a circuit and operable only when the circuit is closed for permitting the controller to transfer right of way to the cross lane in response to actuation of the said actuatable device, means for closing and 25 opening said circuit periodically and in a predetermined relationship with the closure of corresponding circuits at other controllers to restrict the time of transfer of right of way from the main lane to such periodic closings of said circuit, means including a rotary step by step switching mechanism effective after a predetermined number of successive closures of said circuit for permitting the controller to transfer right of way to the cross lane at any time in response to actuation of the actuatable device, and means operable upon the next transfer of right of way from the main lane to render said last 30 named means ineffective so as to again restrict transfer by the controller in response to actuation of said actuatable device to such periodic closings of said circuit.
19. In a traffic signal control system for one of a plurality of intersections of a main lane with cross traffic lanes, the combination of a traffic actuatable device in the cross lane, a traffic signal controller connected to said actuatable device for according right of way normally to the main lane and in response to actuation of the actuatable device transferring it to the cross lane 35 and after a predetermined period retransferring it to the main lane, and a master control unit associated with the right of way controller operable cyclically in time cycles to govern operation of said controller, each cycle of said master control unit having a first and second part, means including a circuit closed only in the second part of such cycle for permitting said controller to transfer right of way to the cross lane in response to actuation of said traffic actuatable means occurring in the first or second part of the 40
- control unit cycle and means for opening said circuit in the first part of the cycle for preventing said controller from transferring right of way during said first part of the cycle, a synchronous motor for driving said master control means for opening and closing said circuit cyclically in step with corresponding units at other intersections, and further means operable after a predetermined number of cycles of the master control unit have elapsed during which there has 45 been no transfer of right of way from the main lane to render said right of way controller immediately responsive to the first actuation occurring thereafter in any part of succeeding of said time cycles. 15
20. In a traffic signal control system for a plurality of intersections of cross traffic lanes with a common main lane having at each intersection a traffic actuatable means in the cross lane, a right of way controller normally according right of way to the main lane and upon actuation of the said actuatable device in the cross lane transferring right of way to the cross lane and retransferring it to the main lane, and a cyclically operating master timer connected to 50 said controller for restricting said controller to so transfer right of way only in predetermined relation with the controllers at other intersections when effective, and means responsive to the time spacing of transfer of right of way from the main lane in response to actuations at any one such controller for rendering said master timer effective as to such one controller when the time spacing of transfer of right of way from the main lane by such one controller is less than 55 a predetermined value and for rendering said master timer ineffective as to such one controller when the time spacing of transfer of right of way from the main lane by such one controller in response to actuations is greater than said predetermined value whereby said one such controller may transfer right of way immediately in response to traffic actuation when said master timer is ineffective. 40
21. A traffic control system for the intersection of a cross lane and a main traffic lane having a traffic actuatable means in the cross lane, a right of way transferring mechanism connected to said actuatable device and normally according right of way to the main lane and operable upon actuation of said actuatable device to transfer right of way to the cross lane and thereafter retransfer right of way to the main lane, master control means connected to said right of way transferring mechanism and operating continuously and cyclically to determine when effective periodic times for such transfer of right of way in response to such actuation and including means operable when the frequency of actuations causing such transfer is less than a certain frequency to render said master control ineffective so as to permit immediate transfer of right of way by said mechanism in response to said actuations at any time, and means operable upon the frequency of actuations causing such transfer increasing to said certain frequency and remaining substantially at said certain frequency to render said master control means effective so as to limit to said certain frequency as a maximum the frequency of further transfer of right 60 of way from the main lane in response to such actuations. 55
22. A traffic control system for the intersection of a cross lane and a main traffic lane having a traffic actuatable means in the cross lane, 70

5 a right of way transferring mechanism connected to said actuatable device and normally according right of way to the main lane and operable upon actuation of said actuatable device to transfer right of way to the cross lane and thereafter retransfer right of way to the main lane, master control means connected to said right of way transferring mechanism to control when effective the time of transfer of right 10 of way in response to such actuation and including means operable when the frequency of actuations causing such transfer is less than a certain frequency to render said master control 15 means ineffective so as to permit immediate transfer of right of way by said mechanism in response to said actuations at any time, and means operable upon the frequency of actuations causing such transfer increasing above said certain frequency and remaining above said frequency to render said master control effective so as to limit between said certain frequency and a predetermined greater frequency as a maximum the frequency of further transfer of right of way 10 from the main lane in response to such actuations.

EDWARD H. EAMES.

CERTIFICATE OF CORRECTION.

Patent No. 2,122,411.

July 5, 1938.

EDWARD H. EAMES.

It is hereby certified that error appears in the printed specification of the above numbered patent requiring correction as follows: Page 12, first column, lines 8 and 9, claim 22, for the words "to control when effective the time of" read and operating continuously and cyclically to determine when effective periodic times for such; and that the said Letters Patent should be read with this correction therein that the same may conform to the record of the case in the Patent Office.

Signed and sealed this 1st day of August, A. D. 1939.

(Seal)

Henry Van Arsdale,
Acting Commissioner of Patents.

5 a right of way transferring mechanism connected to said actuatable device and normally according right of way to the main lane and operable upon actuation of said actuatable device to transfer right of way to the cross lane and thereafter retransfer right of way to the main lane, master control means connected to said right of way transferring mechanism to control when effective the time of transfer of right 10 of way in response to such actuation and including means operable when the frequency of actuations causing such transfer is less than a certain frequency to render said master control 15 means ineffective so as to permit immediate transfer of right of way by said mechanism in response to said actuations at any time, and means operable upon the frequency of actuations causing such transfer increasing above said certain frequency and remaining above said frequency to render said master control effective so as to limit between said certain frequency and a predetermined greater frequency as a maximum the frequency of further transfer of right of way 10 from the main lane in response to such actuations.
